UNITED STATES PATENT OFFICE.

MAHLON E. LAYNE AND SAMUEL N. HALL, OF HOUSTON, TEXAS.

WRENCH.

No. 900,861.

Specification of Letters Patent.

Patented Oct. 13, 1908.

Application filed July 30, 1906. Serial No. 328,497.

To all whom it may concern:

Be it known that we, MAHLON E. LAYNE and SAMUEL N. HALL, citizens of the United States, residing at Houston, in the county of 5 Harris and State of Texas, have invented new and useful Improvements in Wrenches, of which the following is a specification.

This invention relates to wrenches commonly known as pipe tongs and which include a chain to embrace the work.

An important object of the invention is to provide a novel arrangement of handle, jaw and chain whereby the jaw and handle are brought as near as possible into a straight 15 line for the purpose of more effectually balancing the wrench when held in the hand.

Another object of the invention is to have the strain on the free end of the chain come on the adjacent end of the handle rather than 20 upon the jaw.

With these and other objects in view, the present invention consists in the combination and arrangement of parts as will be herein-after more fully described, shown in the 25 accompanying drawing, and particularly pointed out in the appended claims, it being understood that changes in the form, proportion, size and minor details may be made, within the scope of the claims, without departing from the spirit or sacrificing any 30 of the advantages of the invention.

In the drawing: Figure 1 is a side elevation of a wrench embodying the features of the present invention. Fig. 2 is a top plan view thereof, the chain being omitted. Fig. 3 is a front elevation of the wrench. Fig. 4 is an edge view of one of the jaw plates. Fig. 5 is a side view of one of the jaw plates looking at the inner face thereof. Fig. 6 is 40 a view showing one side and the top of the swinging link for anchoring one end of the chain.

Like characters of reference designate corresponding parts in each of the figures of 45 the drawing.

The handle 1 of the present wrench is straight for the greater part of its length, and has its forward extremity or head 2 set at an angle of about 45° to the longitudinal axis of the handle. Just in rear 50 of the head, the handle is reduced in thickness and increased in width, as at 3, the increase in width being entirely at what will be termed the inner edge of the handle with its edge rounded or convexed, so as to fit the

palm of the hand. To each side of the head there is applied a jaw member 4, which is segmental in shape or substantially triangular, having two adjacent edges substantially straight and converged, while its third edge is convexed and provided with the reversely toothed portions 5 and 6, between which is a concavity or seat 7 free from teeth and smooth. One of the toothed portions is integral with the jaw, while the other toothed portion, say that designated 6, consists of a separate block set into a recess 8, in the convexed edge of the jaw and having a shoulder 9 at its inner edge against which the block rests. By preference, there is a tongue and groove connection between the block and the jaw, such as shown at 10. A dove-tailed tongue and groove connection is preferred, as it holds the removable toothed block without extraneous fastenings, it being proposed to upset one or both ends of the tongue to prevent the block from working sidewise out of the recess. Each jaw is centrally pierced by an opening 11, to register with an opening in the deflected end of the handle for the 80 reception of a bolt or other fastening 12, to hold the jaws to the handle. The inner face of each jaw is provided with a seat or recess 13, disposed at an angle of about 45° to the working face or edge of the jaw for the 85 reception of the deflected end of the handle.

The chain 14 has its pivot pins projected at each side of the chain, as at 15, to form studs or projections for individual engagement with the respective jaws to adjust the 90 active length of the chain. One end of the chain has a terminal link 16, provided at its outer end with a cylindrical cross-head 17, the ends of which are reduced to provide studs or projections 18, designed to be received within appropriate sockets or recesses 19 formed in the inner sides of the two jaws so as to pivotally assemble the link with the jaws. The free end of the chain is adapted to pass between the other ends of the jaws 100 and have any pair of studs or projections 15 engaged with notches or seats 20 formed in those straight edges of the jaws which are opposite the link 16.

In practice, the work, say a pipe as shown at 21 is first received within the work-receiving seat or recess 7, and then the chain is passed around the work and engaged with the notches or seats 20 of the jaws, after which the work is permitted to move trans- 110

versely across the seat 7 to one of the toothed portions of the jaws, whereupon the work will become wedged between the said jaw portion and the chain and will be compelled 5 to turn with the wrench.

A very important advantage of the present invention will be appreciated by reference to Fig. 1 of the drawing, from which it will be seen that the chain bears against the 10 forward end of the handle, wherefore the strain upon the free end of the chain will be applied directly to the handle rather than to the jaws, thereby to materially strengthen the wrench and increase the life thereof.

15 It will here be stated that the seats 20 and the pivotal connection between the link 16 and the jaws are located at equal distances at opposite sides of the center of the jaws which is the point of connection between the

20 jaws and the deflected end of the handle. By this arrangement, the work will bind upon each toothed portion or working face of the jaw, and consequently the wrench will work in opposite directions.

25 Concerning the flattening or increasing the width of the handle, as at 3, it will here be explained that, in using the wrench, the palm of the hand is placed against the inner or convexed edge of the enlarged portion 3,

30 whereby the point of support of the wrench, when used upon vertical work, is substantially in line with the inner edge of the widened portion of the handle and the bolt which secures the jaw plates to the handle,

35 which line passes through the center of gravity of the wrench, and consequently the weight of the handle is upon one side of this line and the weight of the chain and portions of the jaws are upon the other side of 40 the line, whereby the wrench is balanced and prevents twisting thereof in the hand.

While it has heretofore been stated that the deflected end of the handle is set at an angle of about 45° of the major portion of 45 the handle, it will here be explained that the angular disposition of the deflected end of the handle is really determined by the general plane of the toothed edges of the jaws, that is to say, the inner face of each plate is 50 provided with a socket 22 disposed substantially at an angle of 45° to said plane of the

teeth, and the deflected end of the handle is received within the sockets of the two plates.

In connection with the engagement of the free end portion of the chain with the forward end of the handle, it will be noted that the studs which are engaged with the notches 55 20 are relieved from strains to a considerable extent.

Instead of having the stud 18 shouldered, 60 as shown in Fig. 6, we contemplate having it of the same diameter throughout its length and integral with the link. Moreover, as shown the stud should be flush with the adjacent extremity of the link, thereby to 65 bring the connection between the link and the jaws as far as possible from the working faces of the jaws.

Having thus described the invention, what is claimed is:

70 1. A wrench comprising a handle and a pair of jaw plates embracing and secured to one end of the handle and provided with oppositely acting faces located at one and the same side of the handle, said handle 75 being flattened and extended laterally in rear of the jaw plates and upon the same side of the handle as the oppositely acting faces, to form a hand grip.

2. A wrench comprising a handle, a pair 80 of jaw plates embracing and secured to one end of the handle and provided with oppositely acting faces at one and the same side of the handle, and a chain to coöperate with the jaw faces with one end secured to and 85 between corresponding ends of the plates and its free end having a detachable engagement with and between the other corresponding ends of the plates, the handle being flattened and extended laterally in 90 rear of the jaw plates and upon the same side of the handle as the oppositely acting faces, to form a hand grip.

95 In testimony whereof we affix our signatures, in presence of two subscribing witnesses.
